AS BARBER-COLMAN COMPANY, OF ROCKFORD, ILLINOIS.

BOBBIN CLEANING AND HANDLING MECHANISM.

1,106,239.

Specification of Letters Patent.

Patented Aug. 4, 1914.

Application filed May 24, 1911. Serial No. 629,134.

To all whom it may concern:

Be it known that I, Burt A. Peterson, a citizen of the United States, residing at Rockford, in the county of Winnebago and 5 State of Illinois, have invented certain new and useful Improvements in Bobbin Cleaning and Handling Mechanism, of which the following is a specification.

In doffing spinning frames it is customary 10 to attach the yarn to the new bobbin by allowing a few wraps of yarn from the doffed bobbin to slip onto the spindle, and then pressing the new bobbin onto the spindle, thereby clamping the yarn between the 15 spindle and the new bobbin. In the course of time, yarn and lint accumulate in the bores of the bobbins to such an extent that it is difficult or impossible to place the bobbins properly upon the spindles.

20 One of the objects of this invention is to provide means for removing such accumulations of yarn or the like from bobbins or other thread-containers.

Another object of the invention is to provide means for feeding bobbins from a container to a means for operating upon the bobbins.

A further object is to provide means for loading bobbins into a suitable magazine.

30 A further object is to produce a machine adapted to automatically remove bobbins from one magazine, clean or strip yarn from the bobbins, and load the cleaned bobbins into another magazine.

35 In the accompanying drawings, Figure 1 is a side elevation of one form of machine embodying the features of my invention. Fig. 2 is an end elevation, and Fig. 3 is a top plan view of the machine. Fig. 4 is a 40 fragmental elevation, taken from the side opposite to that shown in Fig. 1. Fig. 5 is a fragmental vertical central section. Fig. 6 is a sectional view taken in the plane of dotted line 6--6 of Fig. 3. Fig. 7 is a section on dotted line 7--7 of Fig. 3. Fig. 8 is a fragmental sectional view of an air compressor comprised in the machine as herein shown. Fig. 9 represents the valve that controls the discharge of compressed air. Fig. 50 10 is a fragmental plan view of a doffer magazine. Fig. 11 is a sectional detail of said magazine.

The present embodiment of the invention is arranged to receive the bobbin magazine

of a spinning-frame doffer; feed the bobbins 55 from the magazine to a means for cleaning waste from the bores of the bobbins; and place the cleaned bobbins in another magazine, ready to be placed upon the doffer.

The form of magazine herein shown, by 60 way of example, is indicated at *a* and comprises vertical walls united by top and bottom frames *b* *c*. The interior of the magazine is partitioned off into vertical compartments each adapted to contain a single tier 65 or stack of bobbins. As indicated in Fig. 5, the form of magazine herein illustrated is adapted to contain six tiers of bobbins. The upper end of the magazine is open. When the magazine is in place on the doffer the 70 bobbins are withdrawn from the lower end of the magazine. In order that the magazine may be conveniently loaded before it is placed on the doffer, the magazine is provided with a removable bottom *d* (Figs. 10 75 and 11) adapted to fit between opposite sides of the lower frame *c* and against stop flanges *e* on said frame. A locking bar *f* is pivoted at its midportion upon the lower side of the bottom *d*, the ends of said bar being 80 adapted to enter slots *g* in the lower frame *c*. The pivotal movement of the locking bar *f* is limited by stops *h* on the bottom *d*. On the lower side of the locking bar *f* are 85 projections *j*.

The form of bobbin-cleaning and handling machine herein shown comprises a framework 1 including a table 2. Upon the table are fixed two parallel side members 3 4 which support a portion of the mechanism 90 and also provide a seat on which a magazine may be placed in upright position. Displacement of the magazine from its seat is prevented by means comprising, in this instance, guides 5, 6, 7, and 8 (Figs. 3, 4 and 5) 95 fixed to the side members 3 4; two rigid hooks 9 10 (Figs. 3 and 6) on the side member 3 adapted to engage the bottom frame *c* of the magazine; two stops or guides 11 12 on the side member 4; and a hook 13 fixed 100 upon a rock shaft 14 mounted in bearings on the side member 4. A torsion spring 15 normally holds the hook 13 in engagement with the lower frame *c* of the magazine. When the operator desires to release the 105 magazine, he may grasp the hook 13 and swing it away from the magazine, or, if more convenient, he may withdraw said

hook by operating a hand lever 16 fixed to the rock shaft 13.

Below the seat for the magazine is means for withdrawing and replacing the bottom *d*.

5 In the present embodiment of the invention, said means comprises a table 17 (Figs. 3 and 6) guided for vertical movement by means of pins 18 fixed to said table and extending slidably through blocks 19 fixed to 10 brackets 20 that are rigidly attached to the side members 3 and 4. When the table is in its lower position it rests upon the blocks 19. On the side edges of the table 17 are flanges or ribs 21 to prevent lateral displacement of the bottom *d*. When the bottom is 15 resting upon the table 17, the down-turned end flanges *k* (Fig. 5) of the bottom lie at opposite ends of the table and prevent endwise displacement of the bottom. The 20 means herein shown for raising and lowering the table 17 consists of a hand lever 22 pivoted on a shaft 23 mounted in the side members 3, 4, said lever having an arm 24 which has a pin and slot connection with 25 lugs 25 on the table 17.

In the embodiment herein shown, means is provided for unlocking and locking the bottom *d*, which means consists of an angular hand lever 26 pivoted at 27 to the table 30 17 and provided with two lugs 28 adapted to lie at opposite sides of one of the projections *j* on the locking bar *f*.

A magazine filled with bobbins to be cleaned having been placed upon the seat 35 provided therefor on the side members 3, 4, the operator depresses the lever 22 to raise the table 17 into contact with the bottom *d*, the lever 26 occupying a central position, *i. e.*, so that its body portion extends parallel 40 with the locking bar *f*. The raising of the table 17 brings the lugs 28 on the lever 26 at opposite sides of a projection *j* on the locking bar *f*. Holding the table 17 elevated, the operator swings the lever 26 to one side or 45 other of its central position, thereby withdrawing the ends of the bar *f* from the slots *g*, and thus releasing the bottom *d* from the magazine. The table 17 may now be lowered with the bottom *d* resting thereon.

50 Directly below the magazine seat on the side members 3 and 4 is a support for a magazine to receive the cleaned bobbins. In this embodiment said support comprises two rails 29 fixed to the lower side of the table 2 and adapted to support a magazine by its 55 upper frame *b*.

30 is a stop to determine the operative position of the magazine. There is an opening 31 (Fig. 5) through the table 2 directly 60 above the support for the receiving magazine. Vertically aligned with the partitions in said magazine are bars 32 (Figs. 5 and 6) extending between the side members 3 and 4.

The means for feeding bobbins from the 65 upper magazine to the cleaning means and

for moving the cleaned bobbins to a position above the receiving magazine comprises, in this instance, an intermittently-actuated endless chain conveyer comprising two chains 33, 34 running over sprocket wheels 70 fixed on the shafts 23 and 35 which are carried in bearings on the side members 3 and 4. The bearings for the shaft 35 are adjustable, as shown in Fig. 4, to permit of taking up slack in the chains. Fixed to the 75 chains 33, 34 are lugs 36 which form between them recesses to receive the bodies of the bobbins. It will be understood that the form of these lugs may be varied to suit the shape of the bobbins to be carried. The 80 upper runs of the chains 33, 34 are supported upon the brackets 20 and are held from sidewise displacement by flanges 37 (Fig. 7) on said brackets and by plates 38 that are fixed to the brackets 20 and overlie angular 85 portions on the lugs 36. Said plates also prevent the upper runs of the chains from jumping upwardly. The lower runs of the chains are prevented from sagging by rails 39 and are held against upward displacement by rails 40, the rails 39 and 40 being fixed to the brackets 20. While being moved by the upper run of the conveyer, the bobbins ride upon the flanges 37. While passing around the sprocket wheels on the shaft 90 35, the bobbins are guided by two curved guides 41 (Fig. 5) which are continued to form rails 42 on which the bobbins ride until they reach the first bar 32. 43 are converging guide plates which serve to shift the 95 bobbins longitudinally as the conveyer moves, and thus act to bring the bobbins into uniform position on the conveyer. The plates are continued in the retaining plates 44 which extend at both sides of the path of movement of the bobbins from the guides 43 to the farthest bar 32. 44^a is a guard plate to prevent accidental upward displacement of the bobbins.

In the present embodiment of the invention, the operation performed upon the bobbins is the removal of waste yarn, lint or other material from the bores of the bobbins, the clearing of the bobbins being effected, in the particular embodiment herein illustrated, by forcing the material out of the bore by a blast of pressure fluid, such as compressed air. The pressure fluid may be obtained from any suitable source. Herein I have shown an air compressor comprising a cylinder 45 having trunnions 46, 47 journaled in bearings in the machine frame 1. In said cylinder is a piston 48 connected by a rod 49 to a pin on a crank plate 50 (Fig. 2), the latter being fixed upon the drive shaft 51. Said drive shaft is herein shown as provided with a drive wheel 52.

The intake or suction valve for the cylinder 45 is indicated at 53 in Fig. 8. The discharge takes place through a passage 54 ex-

tending through the trunnion 47 and communicating with a pipe 55 which leads to a valve casing 56 (Fig. 7) supported by the side member 3. Said casing is provided with an outlet or nozzle 57 arranged at one side of the path of the bobbins on the conveyer and extending parallel with the axes of the bobbins. The nozzle 57 is provided with a rubber gasket or packing ring 58. The discharge of air from the nozzle is controlled by a continuously rotating valve 59 (Fig. 9) which blanks the inlet to the casing during the compression stroke of the piston 48. Alined with the nozzle 57 and located at the opposite side of the conveyer is a tubular clamping member 60 (Fig. 7) slidably mounted in a bearing 61 and reciprocated toward and away from the nozzle by means herein shown as comprising an arm 62 connected to the clamping member and fixed upon a rock shaft 63, said shaft being rocked in one direction by a spring 64 and in the opposite direction by a cam 65 (Fig. 2) mounted on the drive shaft and acting upon an arm 66 fixed to the rock shaft 63. The clamping member 60 has a flaring mouth to receive the butts of the bobbins.

Above the receiving magazine I provide means to control the descent of the bobbins into said magazine. In the present embodiment, said controlling means comprises means for supporting bobbins by their opposite ends until a predetermined number are ready to be placed in the magazine, and for withdrawing such supporting means to permit the bobbins to drop into the magazine. Said supporting means comprises two parallel rails 67 68 (Figs. 5 and 6) arranged beneath the series of bars 32 and in position to support the ends of bobbins lying between said bars. As the conveyer moves the bobbins along, successive bobbins fall into the spaces between the bars 32, and as these spaces become full the conveyer gradually advances a layer of bobbins onto the layer in said spaces, as shown in Fig. 5. The rails 67 68 are carried by arms 69 fixed to parallel rock shafts 70 which are mounted in bearings on the side members 3 and 4. Fixed to said shafts are arms 71 extending toward each other, the adjacent ends of said arms being pivotally connected by a link 72 to one end of a lever 73. This lever is pivoted close to the point of connection of the link 72 upon a stud 74 which is vertically slidable in the table 2, but which normally is unyieldingly supported by a relatively stiff spring 75. 76 is a stop pin defining the normal position of the stud 74. Fixed on a continuously rotated shaft 77 is a cam 78 arranged to contact and swing the lever 73 downward, upward restoring movement of the lever being produced by a spring 78a. Pivotally supported upon the

shaft 23 is a feeler 79 normally held toward the bobbins by a spring 80, but arranged to be swung by an advancing bobbin so that the hook 81 on said feeler is in the path of the projection or hook 82 on the lever 73. 76 When two layers of bobbins have been positioned above the receiving magazine, as shown in Fig. 5, the feeler 79 has been swung by the advance of the adjacent bobbin into position to interlock with one end 75 of the lever 73 and thus limit the downward movement of that end of the lever. The feeler thus provides an unyielding fulcrum for the lever 73, and the rotation of the cam causes the fulcrum stud 74 to yield downwardly, drawing the arms 71 downwardly and thus swinging the rails 67 68 outwardly, whereupon the two layers of bobbins drop into the magazine. As soon as the cam 78 permits the hooks 81 82 to separate, the spring 80 restores the feeler 79 to its normal position, and the spring 75 raises the fulcrum stud 74 to its normal position, thereby swinging the rails 67 68 inwardly into position to support bobbins. 80 85 90

In the present embodiment, the bobbin-handling mechanisms are driven as follows: On the shafts 51 and 77 are fixed sprocket wheels over which runs a chain belt 83. The valve 59 is rotated by means of a similar belt 84 extending over sprocket wheels fixed to the shaft 77 and the spindle of the valve. The conveyer is moved step-by-step by a Geneva stop motion comprising a pin disk 85 fixed on the shaft 77 and arranged alternately to turn and lock a star wheel 86 fixed on the shaft 23. 95 100

As shown in Figs. 5 and 6, the bars 32 are preferably grooved as at 87 to accommodate the butts of the bobbins. The rail 67 is made of less height than the rail 68 to compensate for the greater diameter of the butts, so that the bobbins shall be supported upon said rails in a substantially horizontal plane. 110

Assuming the machine to be at rest, with the conveyer substantially in the position shown in Fig. 5: The operator places a loaded magazine upon the seat provided therefor in the machine and slides an empty magazine onto the rails 29. The operator then raises the table 17 against the bottom *d* of the full magazine, by means of the lever 22, unlocks the bottom by operating the lever 26, and lowers the table 17, with the bottom 120 lying thereon, onto the blocks 19. As the table 17 and bottom *d* are lowered, the bobbins in the magazine settle, the lowermost bobbin in each compartment entering opposite recesses in the conveyer. The machine 125 may now be set in operation. As the conveyer travels, bobbins from the magazine compartment farthest to the right (Fig. 5) drop into the recesses in the conveyer until that compartment is emptied, when the next 130

compartment begins feeding. At each movement of the conveyer a bobbin is brought into alinement with the nozzle 57 and the clamping member 60, whereupon 5 said clamping member is advanced to clamp the positioned bobbin between said clamping member and the nozzle, immediately following which the valve 59 releases the charge of compressed air. The blast of air, 10 entering the tip end of the bobbin, blows the waste out of the bobbin and through the tubular clamping member 60. Any suitable arrangement (not shown) may be provided to receive the waste. After the bobbin has 15 been cleaned, the clamping member 60 is withdrawn to release the bobbin, whereupon a feed movement is imparted to the conveyer to remove said bobbin from operative relation to the nozzle and the clamping 20 member and to advance another bobbin into position to be cleaned. The cleaned bobbins are deposited by the conveyer in the spaces between the bars 32 and above the bobbins placed in said spaces, whereby the bobbins 25 are arranged in alinement with the compartments in the receiving magazine. When two layers of bobbins have accumulated as shown in Fig. 5, the rails 67 68 are withdrawn, whereupon said bobbins drop 30 into the receiving magazine. These operations are automatically repeated until all of the bobbins have been cleaned and loaded into the receiving magazine.

It will be understood that the embodiment 35 herein shown of my invention is susceptible of various modifications.

I claim as my invention:

1. In a bobbin cleaner, an endless bobbin conveyer, means for imparting a step by 40 step movement to the conveyer, a pressure-fluid nozzle located at one side of the conveyer in the plane of the bobbins lying on the conveyer, and a member located at the side of the conveyer opposite to the nozzle 45 for longitudinally pushing a bobbin lying on the conveyer into contact with the nozzle.

2. In a bobbin cleaner, a pressure fluid nozzle, a tubular clamping member arranged opposite said nozzle, and means for operating 50 said clamping member to clamp a bobbin between said member and said nozzle with its bore in alinement with the nozzle.

3. In a bobbin cleaner, a pressure fluid nozzle, a tubular clamping member alined 55 with said nozzle, and means for reciprocating said clamping member to clamp and release a bobbin.

4. In a textile machine, a seat upon which a bobbin magazine may be removably 60 placed; a support for another bobbin magazine; mechanisms for transferring bobbins from the first mentioned magazine to the second mentioned magazine; and means for removing yarn from the bobbins while 65 in transit between the magazines.

5. The combination of means for removing 75 yarn from bobbins, means for loading a magazine with bobbins, and means for conveying bobbins from the yarn-removing means to the magazine-loading means.

6. The combination of an endless bobbin 75 conveyer, means arranged in the path of the bobbins carried by said conveyer for removing yarn from the bobbins, a support for a magazine, and means above said magazine for intermittently releasing bobbins to gravitational movement into a magazine placed on said support, said conveyer being arranged to carry cleaned bobbins to said releasing means.

7. The combination of an endless bobbin 85 conveyer, means located in operative relation to the path of the bobbins carried by said conveyer for removing yarn from the bobbins, means for supporting a magazine, means for supporting a layer of bobbins above the magazine, and means for periodically withdrawing said supporting means, said bobbin conveyer being arranged to carry the cleaned bobbins onto said bobbin-supporting means.

8. The combination of a support for a magazine, means above the magazine for supporting bobbins, means for placing bobbins upon said support, and means controlled 95 by the presence of a bobbin for withdrawing said support to permit bobbins to gravitate into the magazine.

9. The combination of a magazine support, means for supporting a layer of bobbins above the magazine, means for placing bobbins upon said supporting means, means tending to intermittently withdraw the bobbin-supporting means, and a feeler arranged to be moved by a bobbin into position to 100 render said withdrawing means operative.

10. The combination of a magazine support, a bobbin support above said magazine support, a cam, means for moving said bobbin-supporting means comprising a member having a yieldable fulcrum, said member being normally swung on said fulcrum by said cam, and a feeler arranged to be moved by a bobbin on said bobbin-supporting means and adapted to form an unyielding fulcrum 115 for said member, whereby the cam causes said yieldable fulcrum to yield and thereby withdraw said bobbin-supporting means.

11. The combination of a magazine support, means for forming a layer of bobbins above the support, and means for releasing the layer of bobbins as a unit to gravitational movement into the magazine.

12. The combination of a magazine support, two rails for supporting the opposite ends of bobbins, and means for separating said rails to withdraw them from beneath the bobbins.

13. The combination of a support for a magazine having compartments therein, a

series of bars above said support and providing spaces between them corresponding to the compartments in the magazine, means for placing bobbins between said bars, means for supporting bobbins in said spaces, and means for withdrawing said bobbin-supporting means.

14. The combination of an endless bobbin conveyer, means for supporting a loaded magazine above the conveyer, means for supporting a receiving magazine at the discharge portion of the conveyer, a nozzle located at one side of the path of bobbins carried by the conveyer, means at the other side of said path for holding the bobbins while subjected to the discharge from the nozzle, and means for controlling the entrance of bobbins into the receiving magazine.

In testimony whereof I affix my signature in the presence of two witnesses.

BURT A. PETERSON.
